CARPET.

No. 18,125.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,125, dated March 6, 1888.

Application filed January 26, 1888. Serial No. 262,046. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of a mass of geometrical flower-shaped figures repeated over the surface of the carpet, as shown. The central part

of these figures is ornamented with a net-work of lines. Around this central portion are the 20 flower-leaves, the outlines of which are formed by irregular rectangular lines, as shown. These geometrical flower-shaped figures are grouped together in one continuous mass and overlie one another, some appearing more prominently than others.

What I claim as new, and desire to secure by Letters Patent, is—

The design for carpets, consisting of the 30 geometrical flower-shaped figures, substantially as shown.

JAS. L. FOLSOM.
